WINDOW ADJUSTMENT

Fred C. Osten, Sr., Detroit, Mich.

Application December 12, 1949, Serial No. 132,544

4 Claims. (Cl. 20—12)

1

This invention pertains to a window adjustment, and more particularly to an adjustment that permits the complete removal of the window from a window frame.

The primary object of the present invention resides in a window adjustment that when assembled in a window frame, will permit the expedient removal of the window therefrom.

Another object of the invention resides in a window adjustment that may be assembled in any present or new construction.

A further object of the invention resides in the convenient use of a screwdriver for removing a window from a frame.

A still further object is taught in that with the present adjustment, allowance for normal wear, expansion and contraction of the window and the frame, may be accommodated for; thus convenient operation of the window at all times being extant.

A further object of the present invention is shown in an adjustment, durable and economical of manufacture.

Other objects, will become apparent as the specification proceeds, and more particularly when considered in conjunction with the accompanying drawing containing the several views in which:

Fig. 1 is an elevational view of a window frame, showing my adjustment therein, in dotted lines,

Fig. 2 is a transverse sectional view of the window frame showing the adjustment, taken along line 2—2 of Fig. 1,

Fig. 3 is another detail sectional view of the adjustment taken along line 3—3 of Fig. 2,

Fig. 4 is also a detail sectional view of the adjustment taken along line 4—4 of Fig. 3,

Fig. 5 is a detail sectional view showing the manner in which the adjustment is secured to a conventional window slide channel, and

Fig. 6 is a perspective view of the adjustment alone.

The adjustment is shown in Fig. 1 of the drawing mounted in a conventional window frame generally indicated by the numeral 2, and having upper and lower window sashes 4 and 6 respectively. The sashes are adapted to slide in a pair of spaced apart metal window slide channels. For purposes of illustration and adaptation to my adjustment I show only one of said slide channels indicated by the numeral 8, containing beads 10 and 12 cooperating with the grooves or raceways for raising or lowering the sashes.

The adjustments generally indicated as at 14 are mounted to the slide channel 8, by screws 16

2

in the filler strip 18. Similarly the adjustment is anchored to the window frame by screws passing thru holes 20 in the front flange 22 of the adjustment assembly shown in Fig. 6 of the drawing. The adjustment assemblies are mounted unilaterally on one slide channel only, and in multiple arrangement to complement the size or length of the window.

The pertinent details of construction of the adjustment proper consist in a body portion having the base 24, front flange 22, and rear turned flange 26. A sliding arm, generally indicated as at 28, is formed of two sections 30 and 32 having turned edges 34 for retaining the filler strip 18 and similarly turned portions 36 of greater length adapted to slide thru an aperture 38 at one side of flange 22 of the body portion.

A guide channel 40 is aligned with the aperture 38 adapted to guide the sliding arm 28 as it is moved by means to be presently described. The guide channel 40 is formed channelwise as shown in Fig. 3, of the drawing, and has a foot flange 42, with tabs 44 passed thru suitable apertures in the base flange 24 and crimped for rigid assembly thereto.

Mounted at the opposite end of the sliding arm 28, and similarly in the front flange 22 is an adjusting means adapted to advance or withdraw the sliding arm 28 within the body portion, as earlier referred to. The slotted head screw 46 journalled in the front and rear flanges 22 and 26, has a square nut 48 threaded thereon. In assembly the nut is positioned so that its flat portion will bear against the base 24 and thus resist turning with the screw 46. In this manner the nut 48 will traverse the length of the screw 46 as it is turned. An actuator arm 50 is slotted as at 56a to grip or embrace the nut 48, and move therewith. The actuator arm is pivoted as at 54 in the base 24 and its opposite end 56 adapted to fit into an aperture 58 formed in the portion 36 of the sliding arm 28.

In operation it can be appreciated by reference to Fig. 6, of the drawing, that by rotation of the screw 46, available for use thru the hole 60 in the trim or garnish moulding 62, the nut 48 will move along the length of the screw 46 and pivot the actuator arm 50 and impart a linear travel of the sliding arm 28 and hence to the window slide channels and sashes for adjustment.

It can thus be appreciated that in the foregoing description a useful, efficient, window adjustment has been accomplished.

While I have shown and described the principal embodiment of my invention, it is obvious that

certain alterations and modifications may be made by those skilled in the art, without departing from the spirit and scope of the invention, and I wish to avail myself of any and all that might come within the scope of the appended claims.

I claim:

1. In a window adjustment of the class described, comprising; a body portion having opposite spaced flanges with a transverse, channel shaped guide positioned therebetween for guiding a sliding arm received at one end in said channel, and having its outer end suitably adapted to receive a conventional window slide channel containing a pair of glass panels in a window frame, said sliding arm being slidably received in one of said flanges and having an aperture at one end receiving the free end of an actuator arm pivoted in said body portion and having its other end formed with a slot embracing the parallel sides of a nut, said nut adapted to have one of its flats bear against said body portion resisting rotation against turning of an adjustment screw also journaled in said spaced flanges, said nut travelling freely along the length of the screw as same is turned imparting radial movement to said actuator arm subsequently translated into a linear movement of said sliding arm for window adjustment.

2. In a window adjustment of the class described, comprising; a body portion having a base and two opposite spaced flanges with a transverse channel shaped guide member therebetween for receiving one end of a sliding arm for sliding movement, said sliding arm having its opposite end adapted to receive a window slide channel for sliding upwardly or downwardly a pair of glass panels in a conventional window frame, said sliding arm projecting through an aperture in one of said flanges, said aperture being in alignment with said transverse channel shaped guide member and affording a contiguous slot or raceway for sliding said sliding arm relative to one of said flanges, and said body portion at its end opposite said sliding arm, having journaled in its said flanges, an adjusting, threaded screw, with its head opposite said end of the sliding arm, and having its threaded length engaging a freely travelling nut, said nut resisting rotation of said screw by having one of its flats bearing against said body portion base, and an actuator arm pivoted mid-between said body portion base transversely, and having an enlarged head slotted to interfit with the parallel sides of said nut and travel therewith, and having a free end interfitting in an aperture in the end of said sliding arm, adapted to slide in said transverse channel shaped guide member, said freely travelling nut and pivoted actuator arm and transverse channel shaped guide member cooperating to

translate a radial movement into a linear path of travel for advancing or retracting the sliding arm for adjustment of a window slide channel in a conventional window frame.

3. In a window adjustment of the class described, adapted for use with a window frame having sashes slidably mounted therein and provided with guide strips for engaging the opposite sides of the sashes, one of said guide strips being moved inwardly and outwardly; an engagement strip positioned inwardly of said movable guide strip and movable toward said window sashes for forcing said guide strip into close relation with said sashes; a supporting plate for supporting said engagement strip; an arm projecting from said supporting plate and extending inwardly of said frame; a rockable arm positioned inwardly of said frame and adapted upon rocking in one direction for moving said arm toward said sash and upon rocking in the opposite direction for moving said arm away from said sash; and a threaded mechanism for rocking said rockable arm in either direction at will.

4. In a window adjustment of the class described, adapted for use with a window frame having sashes slidably mounted therein and provided with guide strips for engaging the opposite sides of the sashes, one of said guide strips being moved inwardly and outwardly; an engagement strip positioned inwardly of said movable guide strip and movable toward said window sashes for forcing said guide strip into close relation with said sashes; a supporting plate for supporting said engagement strip; an arm projecting from said supporting plate and extending inwardly of said frame; a rockable arm positioned inwardly of said frame and adapted upon rocking in one direction for moving said arm toward said sash and upon rocking in the opposite direction for moving said arm away from said sash; and a threaded member rotatably mounted in said frame and fixed against axial movement; and a nut threaded on said threaded member and contacting one end of said rockable arm and movable axially of said threaded member upon rotation of said threaded member for rocking said rockable arm.
